UNITED STATES PATENT OFFICE.

FRED M. CARROLL, OF YONKERS, NEW YORK, ASSIGNOR TO THE TABULATING MACHINE COMPANY, OF ENDICOTT, NEW YORK, A CORPORATION OF NEW JERSEY.

CIPHER-PRINTING SYSTEM FOR ACCOUNTING MACHINES.

Application filed November 11, 1926. Serial No. 147,766.

The invention concerns a printing control system for accounting machines and has for its principal object to provide an improved arrangement for special character printing.

5 A more specific object of the invention is to provide for printing certain selected characters in such machines independently of the usual printing control mechanism.

10 Another object of the invention is to provide for selecting certain characters in such machines for printing independently of the usual printing control system and printing selected ones of such characters simultaneously at a time differing from the usual 15 printing period of such machines.

Another object of the invention is to select certain characters for printing by the printing mechanism which prints other characters.

20 Another object of the invention is to select certain characters for printing by the presence or absence of other characters in adjacent columns.

25 Another object of the invention is to provide separate control systems for printing ciphers and digits.

30 Another object of the invention is to provide an independent control system for cipher printing whose operation is governed by the presence of a significant figure to the 35 left of the cipher.

Another object of the invention is to provide an independent electrical control system for cipher printing governed in its operation by printing devices which effect printing of significant figures.

40 The invention finds a particular field of usefulness in machines of the tabulator and lister types in which certain well known difficulties inherent in the machine structure and operation make it desirable to place the printing devices under a separate control system for the printing of ciphers, total marks, asterisks, etc. Machines of these 45 types are usually provided with type carriers, on which are mounted separate type elements for printing the nine digits and a cipher and in some cases special characters such as asterisks for each denominational 50 order which the machine is to print. The type carriers are cyclically movable to bring each type successively into printing position and printing control mechanism, which may be controlled either directly from perforated records being analyzed or from the ac-

cumulating devices of the machine, selects an appropriate type for printing in accordance with the data represented on the records or entered on the accumulators. The preferred form of the invention permits the type 60 selection for the digits to remain under control of the usual printing control system but provides a separate control system for selecting the cipher and special character type. This latter control system is not 65 governed in its operation by the record perforations or the accumulators but by the presence of a digit or significant figure to the left of the particular column in which a cipher or special character is to be printed. 70 This will be clearer from a specific example and it may be assumed that the number 5008 is to be printed by a printing bank consisting of six type carriers and that the units column is to be printed by the type carrier 75 to the extreme right. The printing of the cipher in the hundreds column in this case is made dependent on the presence of the 5 in the thousands column and the printing device of the latter in printing during the cycle 80 automatically sets a control system from which the cipher will be printed later in the cycle. The cipher in the tens column has no significant figure in the adjacent column to the left and its printing is made dependent 85 on the printing of the first significant figure to the left which is the 5 in the thousands column. The special printing control system in this case must be extended through the hundreds column. This is provided 90 for by normally arranging the special cipher control devices so that each one will cause printing of a cipher if the next higher adjacent one does so, the arrangement being automatically disabled for a particular column by the printing of a digit or significant figure in that column. Thus, if a significant figure is printed in any column ciphers will be printed in all columns to the right in which no significant figures occur and no 95 cipher can be printed to the left of the first significant figure of a number. In the present case in which the printing bank has been assumed to consist of six printing devices the two printing devices corresponding to the two highest denominational orders will effect no printing as they have been selected for no digit printing by the main control of the machine and no significant figure has been printed to the left of them to 105 110

select cipher printing. While the cipher printing control system is thus set during the active digit printing portion of the machine cycle it is not rendered effective until 5 this portion of the cycle is terminated after which an operating mechanism operates all printing devices selected for cipher printing simultaneously.

The invention is peculiarly adapted to 10 electrically controlled machines in which an electromagnet selects the proper type in each denominational order for printing. The special control system in this case consists of a circuit including a plurality of parallel 15 branches each containing a printing control magnet and a circuit closer automatically closed by the printing device of the next higher denominational order in selecting a digit for printing. A second circuit closer 20 in each branch is automatically opened by the printing device to which that branch app pertains in selecting a digit for printing to 25 prevent printing of a cipher during any cycle in which a digit has been printed by the printing device. A manually operated 30 switch is provided to connect together at will the branches pertaining to adjacent denominational orders at a point between the two automatic circuit closers. The tie conductor 35 of this switch contains a circuit closer automatically opened when the printing device of the lower denominational order prints a digit. This manual switch makes it possible to connect any number of adjacent 40 branches in parallel so that their energization will be controlled for cipher printing by the nearest printing device to the left which prints a digit. Thus with all the manual 45 switches closed any printing device which prints a digit will automatically set all cipher printing control devices between itself and the first printing device to the right of itself which prints a digit for cipher printing. This arrangement for printing ciphers in 50 successively lower denominational orders under control of a significant figure can be disabled at any point in the bank by merely opening the proper manually operated switch whereupon the cipher control system 55 will not be continued past the open switch. There will be no cipher printing to the left of the first significant figure of a number as the printer which prints this figure will automatically open the tie conductor between 60 its own cipher control branch and that of the next higher denominational order. The 65 automatic circuit closers when set by the printing devices remain set until towards the end of the cycle and the cipher printing control circuit including all its closed branches is energized momentarily after the 70 digit printing portion of the cycle whereupon the cipher type are simultaneously selected for printing on all appropriate type carriers.

The invention is illustrated by way of example in the accompanying drawing which shows a lister equipped with an electrically controlled cipher printing system substantially similar to that just explained although 70 wherever possible common elements have been used for the several circuit closers to conserve material and simplify the wiring. In the drawing:

Fig. 1 is a diagrammatic arrangement 75 showing in section the printing drum and cipher control mechanism operated thereby.

Fig. 2 is a longitudinal section of the cipher control device to a larger scale.

Fig. 3 is a fragmentary view showing the 80 manually operated switch of the cipher control device in open position.

Fig. 4 is a detail illustrating a plugging arrangement to permit one of the cipher control devices to be connected to the print- 85 ing magnet.

Fig. 5 is a section on line 5—5 of Fig. 2.

Fig. 6 is a section on line 6—6 of Fig. 2.

Fig. 7 is a section on line 7—7 of Fig. 2.

Fig. 8 is a circuit diagram showing the 90 operation and control circuits of the machine.

Fig. 9 is a fragmentary detail illustrating the type selecting operation and showing a portion of the mechanism in Fig. 1 to a 95 larger scale, and

Fig. 10 is a detail showing parts of the mechanism in Fig. 10 in another position.

The general operation of the machine may be understood from the circuit diagram in 100 Fig. 8 in which the circuit arrangement to the right in the drawing is substantially a duplicate of that shown in my prior U. S. Patent 1,516,079, filed Nov. 18, 1924 to which reference should be had for a complete description of the listing mechanism and the operation of these circuits. These features will only be explained in the present case sufficiently to permit of a clear understanding of their relationship with the cipher printing control mechanism. In Fig. 8 a source of energy is shown at 20 for energizing the electric circuits of a machine with a switch 21 for disconnecting it from the circuits when desired. Closure of the 115 switch 21 energizes the motor 22 which begins to rotate. But this in itself does not cause feeding of the record cards as the card feed shaft is magnetically operated by a one revolution clutch of a type well known in the art which is controlled by the card feed clutch magnet 23. Card feed may be instituted by depressing the start key 24 thereby 120 rocking the lever 25 and closing contacts 26. The card feed clutch magnet 23 will 125 then be energized through a circuit extending from the positive side of the source of energy 20 through switch 21, wires 27 and 28, through start contacts 26 and card feed relay 29, card feed clutch magnet 23, thence 130

through stop key contacts 30 normally closed, wire 31 and cam contacts 32 closed at this time thence through wires 33 and 34 back to the negative side of the source of energy 20. The energization of card feed clutch magnet 23 permits the card feed clutch to engage and feeding of the record cards ensues. The depression of the start key 24 need only be instantaneous as the card feed relay 29 which is in series with the card feed clutch 23 is energized, closing a stick circuit for the clutch magnet and shunting the start key contacts 26 out of circuit. The cards then continue to feed regardless of the position of the start key 24. The first card in feeding through the analyzing brushes operates the card levers 41 and 42 causing them to close their respective contacts, these levers being held to close their contacts by the cards in feeding until all the cards are fed out of the delivery rack or until a stop card feeds under the brushes. The card lever 42 in closing its contacts removes the control of the card feed clutch 23 from the relay 29 and establishes another circuit for it extending from the positive side of the source of energy 20 through switch 21, wires 27 and 43 to card lever contacts 42 thence through wire 44, card feed clutch 23, stop key contacts 30, wire 31, contacts 32 and wires 33 and 34 back to the negative side of the source of energy 20. This circuit is maintained closed to insure card feed as long as the card lever 42 is operated by cards to close its contacts. The establishment of this circuit short circuits the relay 29 releasing its armature and permitting its contacts to open. The card feed may be stopped manually by depressing the stop key 45 opening its contacts 30 which are in series with the card feed clutch 23. It will be stopped automatically by release of the card lever 42, whose contacts are also in series with card feed clutch magnet 23. The lever 42 may be released of course, either by a stop card or when the last card feeds out of the storage rack.

A stack of cards is shown at 51 in position to be fed to the analyzing device which in the present case consists of a conducting block 52 in which are fixed a plurality of analyzing brushes 58 each individually engaging a contacting block 53 connected to a socket 54 on plug board 55. The brushes 58 resiliently engage the contacts 53 and make electrical contact therewith except when a record card is passing under them. The brushes 58 are energized momentarily for each possible index point on the record card, the energizing circuit extending from the block 52 through a wire 56, cam contacts 57, wire 58, upper contacts of card lever 41 and wires 58 and 27 to the positive side of the source of energy 20. This energizing

circuit will be broken by the card lever 41 whenever a record card is not under the brushes. When the cards are feeding the brush energizing circuit is closed intermittently by contacts 57 operated by a constantly rotating dentated cam 59. The cam 59 is designed to close the contacts 57 substantially simultaneously with the encountering of a perforation by the brushes 58 and to open the contacts 57 before the brushes clear the perforations, thus obviating any possibility of sparking at the analyzing brushes.

The printing control magnets shown at 62 are connected by the common wire 34 to 80 the negative side of source of energy 20 and also to individual sockets 63 on the plug board 55. The sockets 63 are each connected to a contact which is adapted to be bridged to a corresponding contact connected with sockets 61 by bridging contacts 67 insulated from each other and mounted on switch bar 64. The switch bar 64 is operated by a spring 65 and constantly rotating cam 66 to permit bridging between 90 the sockets 61 and 63 during the time when the analyzing brushes are searching the index points from 9 to 1 on the record cards but to remove the bridge during the remainder of the cycle. By properly plugging between the sockets 54 and 61 any analyzing brush may be connected to control any printing magnet 62, thus permitting flexibility of operation of the machine. The brushes 58 on encountering a perforation in a record card make electric contact with corresponding blocks 63 and extend the brush energizing circuit traced above to the sockets 54 and through suitable jumpers to the sockets 61 thence across the switch bar 100 bridging contacts to sockets 63 and through printing magnets 62 and wire 34 back to the negative terminal of source of energy 20.

A printing magnet whose corresponding analyzing brush encounters a perforation of the card will therefore be momentarily energized through a circuit extending through the analyzing brush, which energization of the printing magnet effects printing as will be hereinafter explained. Printing of any 115 of the digits from the record card will be effected in the manner just described which is substantially similar to the operation of the device described in my prior patent above referred to.

The control of cipher printing is entirely removed from the analyzing brushes and relegated to special control devices shown diagrammatically in Fig. 8 at 71 to 74, inclusive, and illustrated in detail in Figs. 120 125 1 to 7, inclusive. The operation of these devices will first be explained in connection with the circuit diagram in Fig. 8 in order to bring out their cooperation with the several circuits of the machine and they will 130

then be described in detail in connection with the remaining figures.

Each of the control devices 71 to 74 has a contact 75 which may be plugged by suitable plugs and sockets indicated at 200 to control any printing magnet 62. This permits a certain amount of flexibility in connections although as will appear later physically adjacent control units must be selected to control in adjacent denominational orders. For example, if the unit 74 is selected to control in the hundreds column, unit 73 must be selected for the tens column and unit 72 for the units column. Each line through which a printer magnet may be connected to a cipher printing unit includes cam contacts 174 which are automatically closed by the machine during the cipher printing portion of the machine cycle but open during the digit printing portion of the cycle. The purpose of these contacts is to prevent back circuits through the printing magnets which might otherwise be established through the cipher control units and effect undesirable printing of digits. Each unit receives an energizing pulse once each cycle during the cipher printing period from cam contacts 85 which are connected to a contact 78 on each unit. The contacts 78 are in parallel with each other and any of the cipher printing control operations may originate in connection with any control unit independently of the status of any other unit. Each unit is provided with additional contacts 76 and 35 77 which are each conventionally shown in Fig. 8 as a plurality of separate contacts electrically connected although in reality they each consist of a single piece of metal. A shiftable switch lever 79 on each unit normally bridges its contacts 75, 76 and 77, but is automatically shifted on any unit whose associated printing device prints a digit to an alternative position in which the bridges across these contacts are removed and the contacts 76 and 78 are bridged. Each control unit has a second shiftable switch lever 80 which may be manually operated to connect contact 76 of its own unit to contact 77 of the adjacent lower unit. As long as the printing device connected with a particular unit does not print a digit its switch arm 79 remains in the position shown in Fig. 8 and the energizing pulse applied to contact 78 has no effect as the circuit is open at this contact. If a digit is printed the lever 79 is automatically shifted to its alternative position and the circuit for the energizing pulse is continued from the contact 78 through lever 79 to contact 76 and 55 through manually operated lever 80, if closed to contact 77 of the adjacent lower control unit. The operation from here on depends on the position of the lever 79 of this lower unit. If the printing device associated with 60 the lower unit has printed a digit during

this same cycle its lever 79 has shifted and the circuit for the energizing pulse is interrupted at the contact 77 and the shifting of the lever 79 of the unit of the higher unit is of no effect. If on the other hand 70 the printing device associated with the lower unit has not printed a digit and must print a cipher the circuit will be continued from its contact 77 through its lever 79 to contact 76 where it divides one branch extending 75 across switch lever 79 to contact 75 and thence to its associated printing magnet 62 to effect cipher printing and the other branch extending from contact 76 across switch lever 80 to contact 77 of the control unit of 80 the next lower unit. The operation of the latter unit is then identical with that just explained and this unit may either interrupt the branch extending through it at its contact 77 or effect cipher printing by its own 85 printing magnet and extend a similar branch to the next lower unit depending on whether or not its lever 79 has been shifted by digit printing. The lever 79 of each unit when shifted in response to digit printing prevents any possibility of cipher printing by its associated printer during the same cycle by automatically disconnecting the contact 75 from any other conducting portion of the unit. Furthermore all the control units of 90 the higher denominational orders are automatically disconnected from a unit which has printed a digit as the lever 79 in shifting disconnects the contact 77 through which the only electrical connection to the 95 higher units can be established, from all other connecting portions of the unit. The switch levers 79 are set during that portion of the cycle when the analyzing brushes are searching the controlling card area 100 covered by the index points from 9 to 1 and remain set until towards the end of the cycle when they are reset. The energizing pulse for cipher printing is applied by closure of the cam contacts 85 after the analyzing 105 brushes have cleared the index points but before the levers 79 have been reset.

The manually operated switch levers 80 permit the contacts 76 and 77 of adjacent units to be disconnected between any two 115 units and the printing devices and cipher control devices can thus be split into separate banks whose operation both as to digit and cipher printing will be entirely distinct.

The mechanical structure and operation of the controlling device is illustrated in Figs. 1 to 10, inclusive. In Figs. 1, 9, and 10 a printing mechanism of the type disclosed in my prior patent referred to above is shown at 101 and consists of a constantly 125 rotating cylinder or drum on which are mounted a plurality of circumferential rows of pivoted type members 102 of which only one row is illustrated in the figure. Ordinarily there will be one row of type mem- 130

bers for each analyzing brush of the machine, and as there are usually 45 brushes the drum will contain 45 circumferential rows of type members. Each type member 102 carries a digit printing type 103 which is adapted to strike a platen roll 104 when the type member is rotated about its pivot. A sheet of paper is fed around the platen roll 104 by paper feed mechanism (not shown) and a printing ribbon is unrolled from the storage roll 105 and rolled onto the receiving roll 106, being suitably guided in the vicinity of the platen roll by guide 107. A printing member 102 when rotated about its pivot will cause its type 103 to strike the ribbon and make an impression of the type on the paper carried by the platen roll. Each type member is provided with a locking cam 111 to hold it positively against rotation about its pivot when it is out of printing position; these cams being rotated once every revolution of the printing drum by suitable gear trains not shown. In the nonprinting positions of the type members the cylindrical surface of the cam 111 rides under the type member and holds it against rotation but on reaching printing position a notch 112 is presented to the type member to permit it to be freely rotated if selected for printing. The rotation of the type member for printing is effected by a lug 113 integral therewith cooperating with a printing finger 115 having a hook at its end to engage the lug 113 when the finger is rocked about its pivot, whereupon the impact due to the rotational inertia of the drum will cause rocking of the type member to effect printing. The printing finger 115 is normally maintained out of the path of the lugs 113 by a spring 116 (Fig. 9) but may be rocked into the path of these lugs through a rearwardly extending arm 117 coacting with a pivoted lever 118. The lever 118 is biased for clockwise rotation by a spring 132 but is normally held from rotation with the spring compressed by the latch lever 121 having a notch 120 which engages an arm 128 integral with the lever 118 as in Fig. 1. The lever 118 has an integral portion extending in proximity to the arm 117 and carrying a pivoted dog 119 resiliently held against the end of the arm 117. The type are selected for printing by momentary energization of the printing control magnet 62 which attracts its armature 126 and through an extension 125 mounted thereon forces a call rod 123 to the right. This call rod is suitably supported and guided in guide members 124 and its movement to the right rocks the latch lever 121 against the action of its spring 122 and releases the arm 128 from the notch 120 in lever 121. The lever 118 is thereupon rotated clockwise by its spring 132 and the resiliently supported dog 119 snaps under the arm 117 as shown in Fig. 9. The lever 118 is provided with a cam surface 133 which shortly after the dog 119 snaps under the arm 117 is engaged by a lug 113 on one of the type members and continued movement of the printing drum cams the lever 118 upward whereupon the dog 119 now being under the arm 117 rocks the printing finger 115 to position the hook at its end in the path of movement of one of the lugs 113 on the printing type 75 as in Fig. 10. While the finger 115 is held in this position by the camming action its notch engages the lug 113 on the proper type member and causes it to rotate about its pivot and effect printing on the paper 80 carried by the platen roll 104. The rotation of the printing drum 101 is synchronized with the passage of record cards past the analyzing brushes so that when the magnet 62 is energized by an index point the 85 type corresponding to this index point will be selected for printing. After the type member has effected printing, the camming action between the surface 133 and the lug 113 of one of the type members continues, 90 rotating the lever 118 further whereupon the resiliently supported dog 119 slips from under the arm 117 and the end of the arm 128 is again seated in the notch 120 in the latching lever 121. The arm 117, being released by the dog 119, the printing finger 115 is rotated counterclockwise by spring 116 to force its end out of the path of the lugs 113 on the printing members. The device is now in position for a subsequent printing 100 operation.

The last two type members 102 have no type members (see Fig. 1) properly positioned behind them to coact with the cam surface 133 and the camming action for 105 these type is effected by projections 134 on cylinders 135 which act exactly as the lugs 113 on the type carriers for the other type. The type member for printing ciphers is indicated at 141 and is spaced several points from the last digit type to allow time for the setting of the cipher printing control circuits and mechanisms. A cylindrical member 143 with an extension 142 is also provided for this type member to coact with the cam surface on lever 118. The printing finger 115, if it selects any digit type for printing during a cycle automatically operates the switch lever 79 of its cipher printing control device to effect cipher printing 110 in the lower adjacent column. The lever 79 is operated by member 151 supported in slots in a bracket 152 fastened to the machine frame 153 (see Fig. 9). The member 151 is provided with an extension 155 which 115 engages the surface of a cam shaft 154 forming a pivot for the member 151 at this point. The end of the member 151 overlies the arm 117 of the printing finger and if the latter is rocked to select a digit type during the 120 125 130

cycle the member 151 will be rocked about the shaft 154 as a fulcrum to set the switch lever 79. The high portion of the shaft 154 is presented to the projection 155 on member 151 during the entire digit printing portion of a cycle and at any time during this portion of a cycle the member 151 may fulcrum about the shaft 154. During the remaining portion of the cycle the low portion of the shaft 154 is presented to the projection 155 and during this time the member 155 slides in its slots in bracket 152 without possibility of fulcruming about the shaft 154. This prevents the switch lever 79 from being operated by the printing of any cipher type or special mark type which might be placed on the drum. At the end of each cycle any switch lever 79 which has been operated during the cycle is returned to normal position by a projection 156 on a constantly rotating shaft 157 which makes one revolution each card cycle.

One of the cipher printing controllers is shown in detail in Figs. 2 to 7, inclusive and consists of side plates 161 preferably of insulating material between which its contacts and switch levers are supported. The contacts 75, 76, 77 and 78 are insulated from each other and lie in planes substantially parallel to the sides 161. The configuration of these contacts will be clear from Fig. 2 in which contacts 75, 78 and 77 are indicated by full lines and contact 76 which lies behind them as shown in the figure is indicated by dotted lines. These contacts are all insulated from each other by suitable insulation indicated generally at 148. The contacts 75, 77 and 78 lie in the same plane and are slightly spaced laterally from the contact 76 as may be seen in Fig. 5. The switch lever 79 is pivoted between the sides 161 and is provided with two conducting extensions 163 and 164 insulated from each other. In the position shown in Fig. 2, the lever 79 has been rocked by the member 151 to select cipher printing and here the conducting extension 164 is forced between lips on the contacts 76 and 78, bridging these contacts to effect cipher printing as explained in connection with Fig. 8. In its alternative or inoperative position, the extension 164 bridges the contacts 76 and 77 and the conducting extension 163 bridges the contacts 75 and 76.

The manually operated switch lever 80 (Figs. 2 and 3) has a conducting extension 165 which at its end 165a is bent back on itself as shown in Fig. 6 causing it to project through an opening 168 in the side 161 and bridge the contact 76 of its own unit to the contact 77 of the adjacent lower unit, the latter contact being bent outwardly at its end as shown in Fig. 6 to extend through a similar opening in the side of its control unit. Adjacent units may be disconnected by rock-

ing the switch lever 80 to the position shown in Fig. 3 in which the conducting portion 165 is removed from engagement with the contacts 76 and 77. In order that the switch arm 80 may coact with adjacent units in this manner it is necessary that the units be mounted very close to each other as shown in Fig. 5 in which two units are illustrated with their sides 161 positioned in slots 162 in the machine frame 153. This closely spaced arrangement incidentally properly positions the automatic switch arm 79 for operation by the members 151 associated with the different printing fingers. The contacts 78 of each unit are electrically connected as indicated in Fig. 8 and a convenient method of automatically effecting this connection as soon as the units are properly positioned in the machine frame is illustrated in Fig. 7 in which each contact member 78 is provided with a looped tongue portion extending through an aperture in the unit and engaging a similar looped tongue on the contact 78 of the adjacent units on each side of it.

Any of the cipher printing control units 90 can be operatively connected to any of the printing magnets 62 by a suitable plug connection illustrated in Figs. 2 and 4. The machine frame 153 has an aperture 181 opposite the normal position of the contacts 75 of each control unit. An insulating sleeve 182 is located in each aperture through which a plug 183 connected to one of the printing magnets 62 may be inserted to make electric contact with the contact 75. This permits any control unit to control any printing magnet.

A complete operative embodiment of the invention has now been described but it will be understood that the details disclosed are not essential to practice the invention, as many modifications will readily occur to those skilled in the art. I intend to be limited therefore only as indicated by the scope of the following claims.

Claims:

1. An automatic printing device comprising a plurality of type and means for selecting said type for printing during a printing cycle, a plurality of independent control systems for said first named means and means for automatically shifting from one control system to another at a predetermined point in the cycle.

2. An automatic printing device comprising a plurality of type and means for moving them successively into printing position during a printing cycle, a plurality of independent printing control systems for said type and means for automatically shifting from one control system to another at a predetermined point in the cycle.

3. An automatic printing device comprising two groups of type, means for selecting the type of one group for printing during

- a portion of a printing cycle and means controlled by the operation of the type of said group for selectively calling the type of the other group for printing and effecting printing thereby when selected during another portion of the cycle.
4. An automatic printing device comprising two groups of type, means for selecting the type of one group and effecting printing thereby during one portion of a printing cycle and means for selectively calling the type of the other group for printing during said portion of the cycle and effecting printing thereby when selected during another portion of the cycle.
5. An automatic printing device comprising two groups of type, means for selecting the type of one group and effecting printing thereby during one portion of a printing cycle and means responsive to the printing operation of type of said group for selectively calling the type of the other group and effecting printing thereby when selected during another portion of the cycle.
6. An automatic printing device comprising a plurality of groups of type, a common selecting mechanism for selecting the type of said groups for printing during a cycle, a plurality of control systems for said selecting mechanism and means for automatically shifting from one control system to another at a predetermined point in the cycle.
7. An automatic printing device comprising a plurality of groups of type, a common selecting mechanism for selecting the type of said groups for printing during a cycle and a plurality of control systems for said mechanism one of which is controlled by the operation of the selecting mechanism for selecting type of one of said groups.
8. An automatic printing device comprising two groups of type, a common selecting mechanism for selecting the type for printing, a control system for said mechanism for governing the selection of the type of one group and operative during one portion of a printing cycle and a second control system for said mechanism for governing the selection of the type of the other group operative during another portion of the printing cycle.
9. An automatic printing device comprising two groups of type, a common selecting mechanism for selecting the type for printing, a control system for said mechanism for governing the selection of the type of one group during one portion of a printing cycle and a second control system for said mechanism controlled thereby in selecting type of said group for printing to selectively call type of the other group for printing during another portion of the cycle.
10. An automatic printing device comprising two groups of type, means for select-
- ing the type of one group and effecting printing thereby, means controlled by said first named means for selecting the type of the other group for printing and means for effecting printing by the type of the latter group when selected subsequent to all printing operations from the type of the first group.
11. An automatic printing device comprising a plurality of serially arranged groups of type, electrically operated devices for selecting the type of each group for printing and a control circuit for each of said devices including a circuit controller operated by the device of an adjacent group.
12. An automatic printing device comprising a plurality of serially arranged groups of type, individual electrically operated devices for selecting the type of each group for printing, and a control circuit for each of said devices including a circuit controller operated by the device of an adjacent group and a circuit controller operated by its own device in selecting a type for printing to render said first named circuit controller inoperative.
13. An automatic printing device comprising a plurality of serially arranged groups of type, individual electrically operated devices for selecting the type of each group for printing and an independent control circuit for each device, an additional control circuit for each device including a circuit controller operated by the device of an adjacent group in selecting a type for printing and a circuit controller operated by the device in selecting a type for printing for rendering said first named circuit controller inoperative.
14. An automatic printing device comprising a plurality of serially arranged groups of type each divided into a main and a subsidiary sub-group, individual electrically operated devices for selecting the type of each group for printing, an independent control circuit for each device for controlling the selection of the type of each main group and an additional control circuit for each device for controlling the selection of the type of the subsidiary group, said additional control circuit including a circuit controller operated by the device of an adjacent group in selecting a type of its main group for printing to effect printing by a type of the subsidiary sub-group in the absence of printing by type of the main sub-group.
15. An automatic printing device comprising a plurality of serially arranged groups of type each divided into a main and a subsidiary sub-group, individual electrically operated devices for selecting the type of each group for printing, an independent control circuit for each device for controlling the selection of the type of each

main sub-group and an additional control circuit for each device for controlling the selection of the type of the subsidiary sub-group, said additional control circuit including a circuit controller operated by the device of an adjacent group in selecting a type of its main group to effect printing by a type of the subsidiary group and a circuit controller operated by the device in selecting a type of its main group for rendering said first named circuit controller inoperative.

16. An automatic printing device comprising a plurality of serially arranged groups of type each divided into a main and a subsidiary sub-group, individual electrically operated devices for selecting the type of each group for printing, an independent control circuit for each device for controlling the selection of the type of its main sub-group for printing and an additional control circuit for each device for controlling the selection of the type of its subsidiary sub-group, said additional control circuit comprising two branches one including a circuit controller operated by the device of an adjacent group in selecting type of its subsidiary sub-group for printing and the other including a circuit controller operated by the device of an adjacent group in selecting type of its main sub-group for printing.

17. An automatic printing device comprising a plurality of serially arranged groups of type each divided into a main and a subsidiary sub-group, individual electrically operated devices for selecting the type of each group for printing, an independent control circuit for each device for controlling the selection of the type of its main sub-group for printing and an additional control circuit for each device for controlling the selection of the type of its subsidiary sub-group, said additional control circuit comprising two branches one including a circuit controller operated by the device of an adjacent group in selecting type of its main sub-group and the other operated by the device of an adjacent group in selecting type of its subsidiary sub-group and a circuit controller operated by each device in selecting a type of its main sub-group for rendering both of said circuit controllers inoperative.

18. In an accounting machine a plurality of printing devices and a plurality of cipher printing control devices each controlled by one of said printing devices to selectively effect cipher printing on another of said printing devices and means for selectively disconnecting each control device from its controlled printing device to permit of independent printing on different printing devices.

19. In an accounting machine, a bank of

successively arranged printing devices and a bank of corresponding cipher printing control devices operated thereby to effect cipher printing to the right of significant figures printed by said printing devices and means for splitting the bank of cipher control devices between any two devices to permit printing of different numbers on different portions of said printing bank.

20. In an accounting machine, a plurality of printing devices and a plurality of cipher printing control devices operated thereby to effect printing of ciphers in the absence of digit printing by any of said printing devices and means for selectively connecting any control device to any printing device to permit control of cipher printing thereon in response to digit printing on any other printing device.

21. In an accounting machine, a plurality of groups of type each consisting of digit type and cipher type, a constantly moving type carrier for supporting said type, means for selecting and operating the type of each group for printing while the carrier is in motion and means controlled by said first named means in response to digit printing by one group to effect cipher printing by another group in the absence of digit printing by said last named group.

22. In an accounting machine, a plurality of groups of type each consisting of digit type and a cipher type and electrically controlled means operated in response to digit printing by one group for selecting the cipher type of another group for printing in the absence of said digit printing by said last named group.

23. In an accounting machine, a plurality of serially arranged groups of type each consisting of digit type and a cipher type, electrically controlled means for selecting the type of each group for printing, a control circuit for said means including a circuit controller operated in response to cipher type selection on any group to select the cipher type of an adjacent group in the absence of digit printing by said last named group.

24. In an accounting machine, a plurality of serially arranged groups of type each consisting of a digit type and a cipher type, electrically controlled means for selecting the type of each group for printing, a cipher printing control circuit for each of said means including a circuit controller operated in response to digit printing by any group to select the cipher type of an adjacent group, a circuit controller operated in response to cipher type selection on any group to select the cipher type of an adjacent group and a circuit controller operated in response to digit printing by any group to disable the circuit for cipher type selection on that group.

25. In an accounting machine, a plurality of electrically controlled printing devices arranged in successive denominational orders and each comprising type for printing 5 digits and a cipher, a control comprising a separate branch for each printing device normally connected in parallel, means operated by each printing device in printing a digit for connecting all of said branches 10 pertaining to lower denominational orders than itself to a circuit energizing device for cipher type selection.

26. In an accounting machine, a plurality of electrically controlled printing devices 15 arranged in successive denominational orders and each comprising type for printing digits and a cipher, a control circuit comprising a separate branch for each printing device normally connected in parallel, 20 means operated by each printing device in printing a digit for connecting all of said branches pertaining to lower denominational orders than itself to a circuit energizing device for cipher type selection and 25 removing the paralleling connection for all branches pertaining to higher denominational orders than itself.

27. In an accounting machine, a plurality of electrically operated printing devices arranged in successive denominational orders 30 and each comprising type for printing digits and a cipher, a control circuit comprising a separate branch for each printing device, circuit closers for connecting any 35 adjacent branches in parallel, means operated by each printing device in printing a digit for connecting all serially adjacent branches pertaining to lower denominational orders than itself which are connected 40 in parallel to a circuit energizing device for cipher type selection.

28. A record controlled machine comprising record analyzing means, a cyclically operable printing device including a plu-

rality of type divided into a main and a subsidiary group, means for selecting said type for printing and separate controls for said means for governing selection of the type in the main and subsidiary groups, one only of said controls including the record analyzing means, and means for automatically shifting from one control to the other at a predetermined point in the printing cycle to permit selection of one group only under direct record control. 45

29. A record controlled machine comprising record analyzing means, a printing device including a plurality of groups of type, each group divided into a main and a subsidiary sub-group, individual electro-magnetic means for selecting each group of said type for printing and separate controls for said electro-magnetic means for governing selection of the type in the main and subsidiary sub-groups, the main sub-group control including the record analyzing means and the auxiliary group control including means operated by main sub-group type selection in an adjacent group. 50

30. A record controlled machine comprising record analyzing means, a printing device including a plurality of groups of type each group including a plurality of significant figure type and a cipher type, an individual electromagnetic device for selecting all type of each group for printing, separate controls for said electromagnetic means for governing the selection of significant figure type and the cipher type, the control for significant figure type selection 55 including the record analyzing means and the control for cipher type selection including means operated by significant figure type selection in another group. 60

In testimony whereof I hereto affix my 65 signature.

FRED M. CARROLL.
